UNITED STATES PATENT OFFICE

RALPH M. SLOUGH, OF FINDLAY, OHIO, ASSIGNOR TO THE OHIO OIL COMPANY, OF FINDLAY, OHIO, A CORPORATION OF OHIO

COMBINED SIGN AND FLOOD LIGHTING APPARATUS

Application filed June 3, 1931. Serial No. 541,917.

This invention has general reference to the class of illumination, and refers more particularly to a combined sign and flood lighting apparatus which, while not necessarily restricted to such use, is especially applicable to automobile filling and service stations.

The invention broadly comprehends an apparatus of the indicated character, by virtue of which a uniform non-glaring, attractive and effectual illumination of the area adjacent the apparatus is obtained, in addition to the accomplishing of a distinctive, sharply defined display and advertising sign and decorative effect which generally enhances and beautifies the premises to which it is applied.

More particularly, the invention resides in an apparatus of the character set forth embodying a member which defines a reflective background surface which serves in the dual capacity of displaying in silhouette, sign elements which are disposed in forwardly spaced relation with respect to the surface and for reflecting a concealed source of light to flood the area adjacent thereto with a soft, non-glaring but effectual and uniform illumination.

The invention aims as a further object to provide a combined sign and flood lighting apparatus which embodies few and simple parts capable of economical production, assemblage and installation and which is highly efficient in its purpose.

With the above recited and other objects in view, reference is had to the following description and accompanying drawings, in which there is exhibited one example or embodiment of the invention, while the claims define the actual scope of the same.

In the drawings:

Figure 1 is a perspective view illustrating the principal application of the apparatus to an automobile filling and service station.

Figure 2 is an enlarged vertical sectional view through the apparatus.

Figure 3 is a horizontal fragmentary sectional view on a reduced scale taken approximately on the line indicated at 3-3 of Figure 2.

Figure 4 is a face view of a modified adaptation of the invention illustrating the manner in which the apparatus may be decorated or ornamented.

Referring to the drawings by characters of reference, the apparatus in its principal application to an automobile filling and service station A or other low building of an equivalent nature, has its coping or parapet B particularly designed to accommodate on its exterior surface the apparatus constituting the present invention, which consists of a member 10, such as sheet metal which is preferably surfaced by white porcelain enamel or the like to provide a combined reflective and background surface 11. In practice, the surface 11 is preferably vertically concave, curved or of a substantially parabolic configuration, to properly project or direct by reflection, light rays from a source of illumination to flood the area adjacent the apparatus, such as the surrounding premises of the building A or the walls or columns of the building. As illustrated, a horizontal bar 12 is supported in any suitable manner such as by the rods 12^a in spaced relation to and in front of the surface 11 of the member 10, to subdivide the same into vertically spaced visible areas C and D. The bar 12 is preferably hollow to provide a tunnel 13 through which lighting wires 14 may be trained to lead to lamp sockets 15 in the rear wall of the bar for the reception of electric lamps 16 which are concealed from view by the body of the bar and by a lower marginal rearwardly projecting shield flange 17. The rear surfaces of the bar 12 may be coated to reflect and intensify the light rays which are cast upon the background and reflective surface 11, whereby the same are in turn projected in the form of flood light therefrom upon the area surrounding and adjacent the apparatus. Sign elements, such as the letters or characters 18, are supported from the member in front of the surface 11 and within the confines of at least one of said visible areas C and D. The sign elements or characters 18 are preferably supported by means of rearwardly extending rods 19, the innermost ends of which extend through apertures

100

in the member 10 and are anchored thereto and into the coping or parapet B. Preferably, the rods 19 are also coated with white porcelain enamel or any other suitable material or substance which minimizes interference with the light reflection. The upper edge 20 of the member 10 may be curved downwardly in order to direct the light rays in the desired path and to the desired distance from the apparatus. The reflected light and the illuminated background surface 11 cause the sign elements or characters 18 to be silhouetted and sharply defined so as to be displayed and visible at a considerable distance.

As illustrated in the modified form shown in Figure 4, the front of the apparatus may be formed with a suitable frame 21 having integral ornamental portions 22 to add to the general effect and esthetic value of the display. In the daytime, the natural light reflected by the surface 11 will serve to sufficiently display the sign elements or characters 18, while at night the artificial lighting will serve in the dual capacity of displaying in silhouette the sign characters and flood lighting the surrounding area.

While there has been illustrated and described a single and preferred embodiment of the invention, it is to be clearly understood that no limitation is intended to the precise structural details, and that variations and modifications which properly fall within the scope of the claims may be resorted to when desired.

What is claimed is:

1. A combined flood lighting and sign apparatus for automobile service stations or the like including a member supported by the coping having a vertically concave reflective and backing surface and formed with a downwardly extending vizor at the upper portion thereof, a bar supported in forwardly spaced relation with respect to said surface and intermediate the height thereof for subdividing the same into vertically spaced visible areas and sign elements supported from and in front of said member within the confines of at least one of said surface areas for silhouetted display against said background.

2. A combined flood lighting and sign apparatus for automobile service stations or the like including a member supported by the coping having a vertically concave reflective and backing surface and formed with a downwardly extending vizor at the upper portion thereof, a bar supported in forwardly spaced relation with respect to said surface and intermediate the height thereof for subdividing the same into vertically spaced visible areas, sign elements supported from and in front of said member within the confines of at least one of said surface areas for silhouetted display against said background and a source of light supported by and in rear of said bar

to afford concealed means for illuminating said reflective surface and background to display said sign elements to flood light the area adjacent said service station.

3. In a combined sign and flood lighting apparatus, a member having an elongated vertically concave reflective backing surface, a bar supported in spaced relation to and in front of said surface and subdividing the same into vertically spaced visible areas, a concealed source of light in rear of said bar for illuminating the surface and flood lighting an area adjacent the apparatus and sign elements supported from said member in front of said surface and within the confines of at least one of said visible areas for silhouetted display against said illuminated background.
